UNITED STATES PATENT OFFICE.

BENJAMIN FRANKLIN LOLLISS, OF BERWYN, ILLINOIS.

ARMATURE MOUNTING.

Application filed February 14, 1924. Serial No. 692,934.

The present invention relates to armature mountings.

The present invention is applicable to and is particularly useful in connection with relay devices such as are used in electric signals. For the reason, among others, that relatively small voltages are used in electric railway signaling devices, it is necessary that the moving parts be nicely adjusted so that no binding will occur to prevent proper movement. It is essential that the armatures responsive to the electro-magnets of the relays be so mounted that they will move freely and with precision in response to energization of said electro-magnets.

It is an object of the present invention to provide a construction involving electro-magnet and armature in which the armature is so mounted that fine adjustment is readily accomplished.

A further object is to provide a construction of armature mounting which combines the advantages of ease of adjustment with certainty that the parts will remain in adjusted position.

A further object is to provide an armature mounting involving a three-point suspension whereby adjustment is readily accomplished.

Further objects will appear as the description proceeds.

Referring to the drawings—

Figure 1 is a view in front elevation of a railway signaling device embodying the principles of the present invention;

Figure 2 is a sectional view taken along the plane indicated by the arrows 2—2 of Figure 1;

Figure 3 is a sectional view on an enlarged scale of part of the mechanism shown in Figures 1 and 2 said sectional view being taken along the plane indicated by the arrows 3—3 of Figure 4;

Figure 4 is a sectional view taken along the plane indicated by the arrows 4—4 of Figure 2;

Figure 5 is a sectional view taken along the plane indicated by the arrows 5—5 of Figure 4;

Figures 6 and 7 are fragmentary views illustrating certain modified details of construction; and

Figures 8 and 9 are fragmentary views illustrating certain other modified details of construction.

Referring first to the construction shown

in Figures 1 to 5, inclusive, the numeral 1 indicates a housing which housing includes a cover 2. The housing may have eight openings indicated by numerals 3—3 which openings may be closed by the transparent closures 4—4. The cover 2 provides mounting means for an electro-magnet 5 which comprises a pair of magnetic cores 6—6 and solenoids 7—7. Said cores 6—6 extend from the exterior of the housing 1 to the interior thereof and are provided interiorly of said housing with pole pieces 8—8. Mounted in co-operative relationship with the pole pieces 8—8 is the armature 9 which is pivotally mounted, in a manner to be described hereinafter, to have a swinging movement toward and away from the pole pieces 8—8. The armature 9 supports a number of contact members 10—10, said contact members being carried at the lower ends of spacing devices 11—11. The contact members carry resilient contact fingers 12—12 adapted to engage with relative stationary contact members 13—13. In the illustrated embodiment of the present invention four contact members 10, four contact members 12 and four contact members 13 are illustrated. It will be understood, of course, that any desired number of contact members may be provided, depending upon the service which the relay device is to perform.

Rigidly united to the pole pieces 8—8 is the bar 14 (see Fig. 3). Said bar 14 may be fastened to the pole pieces 8—8 by means of the screws 15. Said bar 14 may be countersunk for the reception of the heads of screws 15 whereby said bolts will not project beyond the outer face of said bar 14.

Suspended from the bar 14 is the supporting member 16 which supporting member is shown as being of L-shaped cross-section in the illustrated embodiment of the present invention. Said supporting member 16 is provided with a screw-threaded aperture substantially midway of its length which aperture receives the screw 17 adapted to abut against the under side of bar 14 in a region spaced substantially midway of the length of said bar 14. Disposed along axes displaced from the axis of screw 17, but preferably in a common plane therewith, are a pair of holes 18—18 in the supporting member 16, which holes are of sufficient size to allow the free passage therethrough of the shanks of screws 19—19 which have screw-threaded engagement with the support 14.

The heads of said screws 19—19 have abutting relation with the under side of member 16. The screw 17 may be provided with the lock nut 19' whereby said screw 17 may be held in any desired position. As is evident from the drawings, the supporting member 16 is of L-shaped conformation, one leg of which abuts the rear side of the member 14 in a plane substantially parallel with the plane of the axes of the screws 17—17 and 19 and the other leg of which receives said screws 17—17 and 19.

It will be clear that the angular position of the support 16 relative to the bar 14 may be adjusted by manipulation of the two bolts 19—19, the heads of which may be positioned to exert a pressure on the under side of supporting member 16 and that said angular position may be held by turning the bolt 17 so that the tip thereof tightly engages the under side of bar 14.

The supporting member 16 is recessed as indicated by the numerals 20—20 (Figure 4) which recesses provide lugs 21—21 at the extremities of said supporting member. Said lugs 21—21 are screw-threaded for the reception of the screw threaded pins 22—22, providing pintles (Figures 4 and 5) which pintles swingingly support the armature 9. Said screw-threaded pins 22—22 may be provided with lock nuts 23—23 for holding same in position.

The armature 9 is provided near its extremities with the lugs 24—24 having aligned holes, which holes may be provided with bushings 25—25. Each of the screw-threaded pins 22—22 is provided with a cylindrical portion 26 adapted to fit within a corresponding bushing 25 whereby to have a movement of rotation within said corresponding bushing 25.

It will be clear without detailed explanation that by reason of the construction illustrated in Figures 1 to 5 inclusive, the armature 9 may be very nicely adjusted and said adjustment will be maintained throughout service conditions, the bolts 17 and 19—19 provide a three-point suspension for the supporting member 16. The bolts 19—19 will have a sufficiently close fit within the holes 18—18 of the supporting member 16 that movement of said supporting member in a plane normal to the axes of the bolts 19—19 will be prevented. At the same time the slight adjustment of the supporting member 16 which is necessary in service in a plane parallel with the axes of the bolts 19—19 will be readily accomplished by simple manipulation of bolts 19—19 and bolt 17. By manipulation of the lock nut 19' the bolt 17 may be securely locked in position, so that the adjusted position of supporting member 16 will be effectively maintained. The pins 22—22 will be in alignment at all times and adjustment of the sup-

porting member 16 will have the result of adjusting the position of the armature 9 relative to the pole pieces with which they cooperate.

Figures 6 and 7 illustrate a slight modification of the means for supporting the armature 9 from the supporting member 16. According to the construction illustrated in said figures, the lug 21 of the supporting member 16 rotatably carries a pair of non-screw-threaded pins, only one of said pins 27 being illustrated in Figures 6 and 7. Each of said pins may be grooved as indicated by the numeral 28. The numeral 29 indicates a bolt extending through lug 21 in a direction of right angles to the corresponding pin 27. The said bolt 29 fits into the groove of the pin 27 whereby to prevent said pin 27 from withdrawing from the lug 21. The pin 27 is provided with the extension 29 fitting within the bushing 25 carried by the lug 24 of the armature 9.

According to the construction illustrated in Figures 8 and 9, the lug 21 of the supporting member 16 is screw-threaded for the reception of the screw-threaded pin 20. Said lug is slotted as indicated by the numeral 31, said slot communicating with the hole which receives the pin 30. The slot 31 provides the two bifurcations 32 and 33 of which the bifurcation 32 may be provided with the screw-threaded hole 34 and the bifurcation 33 may be provided with the non-screw-threaded hole 35 in alignment with said screw-threaded hole 34. The screw-threaded pin 36 will be provided having the head 37. It will be clear that by turning up the screw-threaded pin 36, the bifurcations 32 and 33 will be moved toward one another to contract the hole which receives the pin 30. By reason of this construction, the pin 30 will be securely held in adjusted position.

It will be understood that the members 14 and 16, the screws and other mounting means associated therewith will preferably be of non-magnetic material whereby to present no interference with the action of the cores 6—6, solenoids 7—7 and armature 9.

It will be understood that the illustrated embodiments of the present invention have been chosen merely for the purpose of illustration and should not be considered in a limiting sense. It is intended that this patent shall include all modifications that fall within the scope of the appended claims.

I claim:

1. In combination, a pair of magnetic cores having adjacent pole pieces, the axes of said cores being parallel with one another, a non-magnetic member secured to said pole pieces, an armature cooperatively associated with said pole pieces, and an armature supporting member for swingingly supporting said armature along an axis par-

- allel with the plane of the axes of said cores, three screws having their axes in a plane substantially parallel with the plane of the axes of said cores for adjustably securing 5 said supporting member to said non-magnetic member, the two outermost of said screws having screw-threaded engagement with one of said members and abutting relationship with the other of said members, 10 the middle one of said screws having screw-threaded engagement with said other of said members and having abutting relationship with the first of said members, whereby the angularity of said armature relative to said 15 pole pieces may be readily adjusted.
2. In combination, a pair of magnetic cores having adjacent pole pieces, the axes of said cores being parallel with one another a non-magnetic member secured to 20 said pole pieces, an armature cooperatively associated with said pole pieces, and an armature supporting member for swingingly supporting said armature along an axis par-

allel with the plane of the axes of said cores, three screws having their axes in a plane 25 substantially parallel with the plane of the axes of said cores for adjustably securing said supporting member to said non-magnetic member, the two outermost of said screws having screw-threaded engagement 30 with one of said members and abutting relationship with the other of said members, the middle one of said screws having screw-threaded engagement with said other of said members and having abutting relationship 35 with the first of said members, whereby the angularity of said armature relative to said pole pieces may be readily adjusted, said armature supporting member having an L-shaped conformation, one leg of which abuts 40 one side of said non-magnetic member in a plane substantially parallel with the plane of the axes of said screws.

Signed at Chicago, Illinois, this eleventh day of February, 1924.

BENJAMIN FRANKLIN LOLLISS.
